UNITED STATES PATENT OFFICE.

FREDERICK D. WEBER, OF EAST NEW YORK, N. Y., ASSIGNOR, BY MESNE ASSIGNMENTS, TO META WEBER, OF SAME PLACE.

PAPER-FILE.

SPECIFICATION forming part of Letters Patent No. 310,758, dated January 13, 1885.

Application filed June 26, 1884. (No model.)

To all whom it may concern:

Be it known that I, FREDERICK D. WEBER, a citizen of the United States, residing at East New York, in the county of Kings and State 5 of New York, have invented new and useful Improvements in Paper-Files, of which the following is a specification.

This invention relates to that class of paper-files in which the sheets are fastened to supporting-leaves which are hinged to fold together in book form; and it consists in the novel features of construction hereinafter described, whereby an article of superior utility is obtained.

15 In the accompanying drawings, Figure 1 is a face view of a paper-file embodying my invention. Fig. 2 is a view looking at the back of the article. Fig. 3 is a cross-section thereof. Fig. 4 is a detail cross-section on the line 20 *x x*, Fig. 1.

Similar letters indicate corresponding parts.

The letter A designates the sheet-supporting leaves, which are hinged together on one edge by means of links B, and provided adjacent to such edge with barbs C, for piercing the sheets of paper to be filed. The links B engage with joint-pins D, which are arranged in knuckles E on the proper edges of the leaves, these knuckles being constructed to accommodate fingers G, which are hung to the joint-pins D at points opposite to the barbs C of the supporting-leaves, and which are provided with slots i to receive the barbs.

In applying the file to use, the sheets are 35 laid on the desired leaves and the latter are folded together, when, by the pressure of the fingers G, the sheets are forced down upon the barbs C, causing the latter to pierce the sheets, and thereby hold them in position on the 40 leaves, the barbs entering the slots of the fingers. The leaves A are composed of sheet metal, and the barbs C are struck up therefrom to project in opposite directions, as shown in Fig. 4, so that the barbs are on opposite sides of the leaves, respectively, and both sides are adapted to receive the sheets to be filed. The fingers G also are on opposite sides of the leaves, so as to accord with the barbs, and the double fingers are made in one 50 piece, they being composed of a strip of sheet metal, which is bent to the shape shown in

Figs. 3 and 4. Each of the leaves A is provided on the free edge with ribs or offsets J, of a height or thickness equal to that of the knuckles E, so that when the leaves are folded 55 on each other spaces are created between them to accommodate the sheets laid upon the leaves, the effect of which is to protect the sheets against pressure. In the example shown the ribs J are on each of the free edges 60 of the leaves A; but, if desirable, the ribs of the end edges, s s, may be omitted, inasmuch as the rib o of the longitudinal free edge suffices to keep the leaves apart from each other.

The number of the leaves A may be varied, 65 and, if desirable, they may be indexed in the manner of a book.

The fingers G may be composed of wires instead of sheet metal, and may be constructed to close elastically instead of by the pressure 70 of the leaves.

What I claim as new, and desire to secure by Letters Patent, is—

1. The combination, in a paper-file, of a series of leaves which are hinged together on 75 one edge and provided adjacent to such edge with barbs for piercing the sheets to be filed, and the slotted fingers hung to the joint-pins of the leaves, for depressing the sheets on the barbs, substantially as described.

2. The combination, in a paper-file, of a series of hinged leaves, of sheet metal, having sheet-piercing barbs struck up therefrom to project in opposite directions, for adapting both sides of the leaves to receive the sheets 85 to be filed, and the double fingers hung to the joint-pins of the leaves, for depressing the sheets on the barbs of both sides of the leaves, substantially as described.

3. The combination, in a paper-file, of the 90 double fingers hung to the joint-pins, and the series of leaves, of sheet metal, having barbs struck up therefrom in opposite directions, and provided at their free edges with the ribs or offsets J, substantially as set forth.

In testimony whereof I have hereunto set my hand and seal in the presence of two subscribing witnesses.

FREDERICK D. WEBER. [L. S.]
